[57] CLAIM

The ornamental design for a transmitter for wireless
light dimmer system, as shown and described.

DESCRIPTION

FIG. 1 is a perspective view of a transmitter for a wire-
less light dimmer system showing our new design;

FIG. 2 is a top plan view thereof;

FIG. 3 is a bottom plan view thereof;

FIG. 4 is a side elevational view thereof;

FIG. 5 is an end elevational view thereof; and

FIG. 6 is an end elevational view thereof, of the oppo-
site side of FIG. 5.

FIG.1
